(57) **CLAIM**

The ornamental design for a lite, as shown and described.

DESCRIPTION

FIG. 1 is a front perspective view of a first embodiment of a lite, showing our new design;

FIG. 2 is a front elevational view, with the rear being a mirror image;

FIG. 3 is a front perspective view of a variation thereof;

FIG. 4 is a front elevational view the rear being a mirror image;

FIG. 5 is a front elevational view of a second embodiment of a lite, with the rear elevational view being a mirror image, showing our new design;

FIG. 6 is a front perspective view thereof;

FIG. 7 is a front perspective view of a variation thereof; and,

FIG. 8 is a front elevational view, with the rear being a mirror image.

1 Claim, 4 Drawing Sheets
